Primary Examiner — Cynthia Underwood(74) *Attorney, Agent, or Firm* — Muncy, Geissler, Olds & Lowe, P.C.(57) **CLAIM**

The ornamental design for a “hinge,” as shown and described.

DESCRIPTION

FIG. 1 is a perspective view of a hinge showing our new design thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view;

FIG. 8 is another perspective view thereof;

FIG. 9 is a perspective view shown reduced in scale and in an environment of use;

FIG. 10 is a perspective view shown reduced in scale, folded into a configuration of use and in an environment of use; and, FIG. 11 is a perspective view shown reduced in scale, folded into another configuration and in an environment of use.

The broken lines shown represent unclaimed subject matter and/or environmental structure and form no part of the claimed design, and.
